UNITED STATES PATENT OFFICE.

GEOERGE D. HUNTER, OF AUBURN PARK, ILLINOIS.

CRIMPER FOR CARTRIDGE-SHELLS.

SPECIFICATION forming part of Letters Patent No. 449,536, dated March 31, 1891.

Application filed October 3, 1890. Serial No. 366,988. (No model.)

To all whom it may concern:

Be it known that I, GEORGE D. HUNTER, a citizen of the United States, residing at Auburn Park, in the county of Cook and State of Illinois, have invented certain new and useful Improvements in Crimpers for Cartridge-Shells; and I do hereby declare the following to be a full, clear, and exact description of the invention, such as will enable others skilled in the art to which it appertains to make and use the same.

My invention relates generally to devices for crimping the outer or front ends of the paper or pasteboard cartridge-shells used in breech-loading shotguns, and particularly to improvements in this class of devices which render them more durable than usual and effective in operation or capable of smoothly and perfectly closing the ends of said cartridge-shells after the powder, shot, and wads have been placed in their respective positions therein; and it consists in the peculiarities of construction and arrangement or combination of parts and features hereinafter fully disclosed in the description, drawings, and claims:

The object of my invention is to provide a crimper for cartridge-shells which will be more durable or last longer than those usually employed, which will avoid the great amount of friction usually pertaining to crimpers manufactured wholly of brass or other metal, which will lessen the usual tendency to tear or roughen the ends of the paper shells of cartridges while they are being inturned or crimped, which will be capable of employment in stationary or portable machines for loading and crimping cartridge-shells, in separate crimping-machines, in separate machines for cutting and crimping cartridge-shells which may have been filled by hand, or in a machine, for instance, of the character of that disclosed in the Letters Patent granted to me May 29, 1888, No. 383,529, and which will be simple in construction, easy to operate, and cheap to manufacture. This object is accomplished by the improved construction and arrangement or combination of the parts and features of this invention, which is embodied in the slightly different forms or constructions shown in the accompanying drawings con-

stituting part of this specification, in which the same reference-numerals indicate the same or equivalent parts, and in which—

Figure 1 represents sectional and front views of one of my improved crimpers for cartridge-shells; Fig. 2, similar views of a modified form or construction of the same, and Fig. 3 similar views of another slightly-modified form or construction thereof.

60

In the drawings, the numeral 1 indicates my improved crimper, which, as shown in Fig. 1 of the drawings, is composed of the main holder 2, the auxiliary holder 3, the glass crimping-disk 4, the cement 5, and the shaft-head 6. These main and auxiliary holders are made of metal, and the former is constructed in the shape of a collar, which is interiorly screw-threaded and enlarged along its rear portion 7, contracted along its front portion 8, and formed with an inturned flange 9 around its front end or rim, while the latter has the shape of a flat-bottomed cup, which is held in place within the former by the exteriorly-screw-threaded and enlarged shaft-head 6, which is removably fitted in the former and when in place holds the front end or rim of the latter firmly against the inturned flange 9 of the former. In the chamber of the cup-shaped auxiliary holder 3 is fitted the glass crimping-disk 4, which is shaped to substantially correspond to the interior thereof and is firmly seated or embedded in the layer of plaster-of-paris, white-lead, or other suitable cement 5. On or in the rear surface of this glass crimping-disk are formed the small ribs or grooves 10, which are pressed into the cement for preventing said disk from turning and for holding the same firmly in place in all directions. The auxiliary holder 3 is prevented from forward displacement by the inturned flange 9 around the front end of the main holder 2, which will keep it from outward or forward movement; also, said auxiliary holder, with its previously-seated glass disk, is placed within said main holder by being passed forwardly through the opening in the enlarged rear portion thereof before the shaft-head 6 is introduced. The front or operative surface of the glass crimping-disk 4 is formed with the raised center 11, the rim 12, the intermediate annu-

lar groove 13, and the bosses or slightly raised projections 14 near the bottom of said groove.

A cartridge - shell while being closed or crimped is required to be firmly supported at its rear end and prevented from turning.

A device for accomplishing this result may be the same as the chuck-cups or shell-rests used in connection with the ordinary cartridge-crimpers, or it may be the same as the adjustable chuck - wheel disclosed in my above-named patent, which is capable of receiving and firmly holding the rear ends of cartridges of various sizes.

In the modified form of construction of my improved crimper shown in Fig. 2 of the drawings the glass crimping-disk 4 has the same construction and is secured in the cement the same as the one above described. The main and auxiliary holders 2 and 3, however, are differently constructed from those above described, as said main holder is formed integrally with the shaft-head 6, as it is interiorly screw-threaded along its front portion, and as it has no inturned flange around its front end or rim, but may have, if desired, while said auxiliary holder is exteriorly screw-threaded for holding it in place or in engagement with the interiorly-screw-threaded front portion of said main holder.

In the additional modified form or construction of my improved crimper shown in Fig. 3 of the drawings the main and auxiliary holders 2 and 3 are connected by screw-threads in the same manner as the corresponding parts in Fig. 2. However, they and the glass crimping-disk 4 are differently constructed from the corresponding and equivalent parts shown in Figs. 1 and 2 in the following particulars: The main holder and the shaft-head are made hollow, and with the auxiliary holder and the glass crimping-disk are formed with the central registering openings 15, which are designed to receive the adjustable or movable center 16, which is in common use for pressing upon the upper wads of charges in cartridge-shells for holding them down while the crimping of said shells is taking place; also, the auxiliary holder 3 of this embodiment of my invention is formed at its front end or rim with an outwardly-turned and milled flange 17 for screwing it into and unscrewing it from the main holder. At a point opposite the bottom of the auxiliary holder of each crimper 1 an annular channel 18 is formed in the inner surface of the main holder 2 for the purpose of facilitating the making of its internal screw-thread.

I do not herein broadly claim a crimper for cartridge-shells provided with a glass crimping-disk, as this and certain other improvements in such devices form the subject-matter of another application for Letters Patent, filed by me simultaneously herewith, Serial No. 366,989; but it will be obvious from the foregoing that my present improvements will avoid all the frictional disadvantages that are incident to the use of brass and other wholly

metallic crimpers, in which the bosses or slightly-raised projections wear out in a very short time and roughen the paper from which the shells are made; that the glass disk will make smoother crimps in shells than when wholly metallic crimpers are employed; that the seating or embedding of said glass disk in cement holds it firmly in place, insures it against easy breakage, affords it a true or level seat within the flat-bottomed auxiliary holder, and permits the outside of the main holder to be turned true after said disk and its holder have been placed in operative position within said main holder, whereas when the entire crimper is made of metal it is generally cast and then swaged to the desired size, which cannot be done with certainty or accuracy owing to the roughness and shrinkage of the metal, and that a crimper provided with this glass crimping-disk will turn over or crimp dry paper shells of cartridges without any twisting strain thereon whatever, will operate with less friction than metallic crimpers, and consequently will require less power for its operation.

Having thus fully described the construction and arrangement or combination of the parts and features of my invention, its advantages, and operation, what I claim as new is—

1. A crimper for cartridge-shells, provided with a main holder, an auxiliary holder, and a glass crimping-disk arranged and secured within the latter, substantially as described. 100

2. A crimper for cartridge-shells, provided with a main holder, an auxiliary holder secured therein and formed with a flat bottom, and a glass crimping-disk arranged and secured within the latter, substantially as described. 105

3. A crimper for cartridge-shells, provided with a main holder, an auxiliary holder secured therein, a layer of cement in the latter, 110 and a glass crimping-disk firmly seated or embedded in said cement, substantially as described.

4. A crimper for cartridge-shells, provided with a main holder, an auxiliary holder secured therein, a layer of cement in the latter, 115 and a glass crimping-disk firmly seated or embedded in said cement and formed with a series of small ribs or grooves on or in its rear surface, substantially as and for the purpose described. 120

5. A crimper for cartridge-shells, provided with a main holder, an auxiliary holder secured therein, an inturned flange around the front end of said main holder, and a glass 125 crimping-disk arranged and secured within said auxiliary holder, substantially as described.

6. A crimper for cartridge-shells, provided with a main holder, an auxiliary holder secured therein, a layer of cement in the latter, 130 a glass crimping-disk seated or embedded in said cement and formed with a series of small ribs or grooves on or in its rear surface,

and an inturned flange around the front end of said main holder, substantially as and for the purpose described.

7. A crimper for cartridge-shells, provided with a main holder, an auxiliary holder secured therein by screw-threads, and a glass crimping-disk arranged and firmly secured within the latter, substantially as described.

8. A crimper for cartridge-shells, provided with a main holder having an inturned flange around its front end, an interiorly-screw-threaded rear portion, an exteriorly-screw-threaded and removable shaft-head therein, an auxiliary holder, and a glass crimping-disk firmly secured within the same, substantially as described.

9. A crimper for cartridge-shells, provided

with a main holder having an inturned flange around its front end, an interiorly-screw-threaded rear portion, an exteriorly-screw-threaded and removable shaft-head therein, an auxiliary holder, and a glass crimping-disk firmly secured within the same in a layer of cement and formed with a series of small ribs or grooves on or in its rear surface, substantially as and for the purpose described. 20 25

In testimony whereof I affix my signature in presence of two witnesses.

GEORGE D. HUNTER.
